(57) **CLAIM**

The ornamental design for an electronic device holder, as shown and described.

DESCRIPTION

FIG. 1 is a rear perspective view of the electronic device holder, showing the new design;

FIG. 2 is a front perspective view thereof;

FIG. 3 is a top view thereof;

FIG. 4 is a bottom view thereof;

FIG. 5 is a back view thereof;

FIG. 6 is a front view thereof;

FIG. 7 is a left side view thereof;

FIG. 8 is a right side view thereof;

FIG. 9 is a perspective view showing the electronic device holder secured within a non-limiting inside area of a vehicle; FIG. 10 is a front view showing the electronic device holder secured within the non-limiting inside area of a vehicle; and, FIG. 11 is a perspective view showing the electronic device holder holding a non-limiting electronic device.

The broken lines shown in FIGS. 9 through 11 form no part of the claim design and merely illustrated one non-limiting intended use. The vehicle, as a non-limiting example for the location of the holder, and the phone, as one non-limiting type of electronic device that can be held or supported by the holder, are shown in phantom for illustrative purposes only and form no part of the claimed design.
